CLAIM

The ornamental design for a grooved guide cage, as shown and described.

DESCRIPTION

FIG. 1 is a top-front-left perspective view of a grooved guide cage, according to the present invention;

FIG. 2 is a right side view of the grooved guide cage of FIG. 1.

FIG. 3 is a left side view of the grooved guide cage of FIG. 1.

FIG. 4 is a rear view of the grooved guide cage of FIG. 1.

FIG. 5 is a front view of the grooved guide cage of FIG. 1.

FIG. 6 is a top view of the grooved guide cage of FIG. 1.

FIG. 7 is a bottom view of the grooved guide cage of FIG. 1.

FIG. 8 is a bottom-rear-left perspective view of the grooved guide cage of FIG. 1.

FIG. 9 is a cross-sectional view taken along line 21-21 in FIG. 3.

FIG. 10 is a cross-sectional view taken along line 22-22 in FIG. 2.

FIG. 11 is a cross-sectional view taken along line 23-23 in FIG. 4; and,

FIG. 12 is a cross-sectional view taken along line 24-24 in FIG. 5.

The dash-dash broken lines in FIGS. 1-12 illustrate portions of the grooved guide cage that form no part of the claimed design.

The oblique broken line hatch shading in FIGS. 9-12 illustrates interior structure of the grooved guide cage that forms no part of the claimed design.

The dash-dot-dash broken lines in FIGS. 2-5 form no part of the claimed design.
